UNITED STATES PATENT OFFICE.

GEORGE F. ATWOOD, OF NEWARK, NEW JERSEY, ASSIGNOR TO WESTERN ELECTRIC COMPANY, INCORPORATED, OF NEW YORK, N. Y., A CORPORATION OF NEW YORK.

CONVEYING APPARATUS.

1,292,227.

Specification of Letters Patent. Patented Jan. 21, 1919.

Application filed December 29, 1916. Serial No. 139,578.

To all whom it may concern:

Be it known that I, GEORGE F. Atwood, a citizen of the United States, residing at Newark, in the county of Essex and State of New Jersey, have invented certain new and useful Improvements in Conveying Apparatus, of which the following is a full, clear, concise, and exact description.

This invention relates to conveying apparatus and is particularly useful in connection with the conveying of "toll tickets" in telephone exchanges.

It is the practice in telephone exchanges to route toll calls to "recording operators" whose duty it is to enter upon a ticket certain data necessary for the setting up of the desired connection. Such tickets are then sent to a "line operator" who arranges for the desired connection and supervises it.

The line operator indicates on the ticket the time duration of the conversation and then sends the ticket to a filing clerk who furnishes information as to the cost of the call, and from whom the ticket finally goes to the

bookkeeper.

The invention is hereinafter described as applied to conveying apparatus for carrying tickets from one or a plurality of recording operators to one or a plurality of line operators and thence to a ticket filing clerk.

Before describing the embodiment of the invention shown in the drawings hereto annexed, attention is called to the fact that a conveying apparatus for use in connection with a telephone switchboard must be almost noiseless in its operation. In order to be accessible to the recording and the line operators, it is almost essential that the mechanism be mounted upon the switchboard, and the least vibration or noise in the moving parts is, of course, highly objectionable because it is audible in the telephone circuits. It would not be difficult to satisfy this requirement for practically noiseless operation if the path over which it is desired to convey tickets were substantially straight. Owing to the fact, however, that the switchboards in a toll office may be of different heights and may be arranged at various angles and levels with reference to one another, the problem of providing a

noiseless conveying apparatus is rendered extremely difficult of solution.

The general object of the present invention is to provide a new and improved form of conveying apparatus which is practically noiseless and vibrationless, and which provides efficiently for the transfer of tickets from certain positions to other positions of a telephone switchboard or to other points in the exchange. In carrying out this general object, certain important details of construction are provided which are herein-after described and claimed. One of these details of construction is the arrangement of the troughs in which the tickets travel, such that the insertion of a ticket in the proper trough is facilitated. Other details of construction relate to the track, the carriage which travels thereon, the supporting arrangement for the traveling belt or rope which moves the carriage, and other details which coöperate with these parts. Still another feature of the apparatus is a device for elevating and depositing a ticket in one of the troughs, this being particularly useful at the line operators' positions for the insertion of the tickets into the trough which conveys them to the ticket filing clerk. Other features of the present new and improved conveying apparatus will be hereinafter specifically pointed out.

In the drawings, Figure 1 is a perspective view, somewhat diagrammatic in form, showing the switchboards of a telephone toll office provided with a conveying apparatus according to the present invention; Fig. 2 is a plan view of that end of such apparatus shown at the extreme right in Fig. 1; Fig. 3 is a cross sectional elevation on the line 3—3 of Fig. 2; Fig. 4 is a side elevation of the elevating portion of the conveying apparatus; Fig. 5 is an elevation of the elevating portion of the apparatus looking in the direction of travel, certain parts being shown in section and certain parts being broken away; Fig. 6 is a fragmentary plan view showing the relative arrangement of the troughs, track and traveling member or rope at a curve; Fig. 7 is an elevation showing the relative arrangement of the track, rope and idler pulleys; Fig. 8

is a fragmentary perspective view showing particularly the carriage, various positions of the finger mounted on the carriage being shown in dash lines; Fig. 9 is a fragmentary 5 perspective view showing how the carriage is connected to the rope; Fig. 10 is a fragmentary sectional elevation showing how the upper wheels are mounted upon the carriage; Fig. 11 is a fragmentary sectional 10 elevation showing the manner in which the ends of the rope are jointed together; Fig. 12 shows in elevation, a delivery chute, and also an elevating mechanism by which tickets may be raised and inserted in one of the 15 troughs; and Fig. 13 is a sectional elevation on the line 13—13 of the delivery chute and elevating mechanism shown in Fig. 12.

From Fig. 1, a general idea may be obtained as to the construction of a conveying 20 apparatus embodying the present invention and as to the manner in which it performs its functions. This view is, of course, largely diagrammatic and for an understanding of the details of construction, reference should 25 be made to the other figures hereinafter described. It will also be understood that the particular arrangement of conveying apparatus shown in Fig. 1 is merely illustrative and that the invention may be embodied in 30 many other arrangements adapted to suit particular needs.

Referring to Fig. 1, the switchboard positions of the recording operators are indicated at A, the switchboard positions of the 35 line operators at B, and the desk of the ticket filing clerk at C. The function of the conveying apparatus is to carry tickets from any one of the recording operators' positions A to any desired one of the line operators' 40 positions B; and to carry the tickets from the line operators' positions B to the ticket filing clerk's desk C. The conveying apparatus is shown mounted upon the top of the switchboards and the desk of the ticket filing 45 clerk. The tickets are conveyed in troughs along which they are pushed by propelling means which moves along the mouths of the troughs and engages the tickets which are of such a size that they project therefrom. 50 These troughs are preferably of sheet metal and offer but little resistance to the movement of the tickets therein. The troughs in which the tickets are conveyed from the recording operators' positions A to the line 55 operators' positions B are shown at D extending in front of the positions A and thence extending onward to the positions B where each trough terminates in a chute such as D¹, D² and D³ projecting downward 60 between two switchboard positions B, thereby enabling two line operators to receive tickets from the same trough. In front of the recording operators' positions A, the troughs D are arranged with their mouths

in step formation, thereby facilitating the 65 insertion of tickets into any desired trough according to the line operator to which the recording operator desires to send the ticket. Suitable inscriptions may be placed upon the walls of the troughs D at this point in 70 order to indicate the switchboard positions B to which particular troughs lead. Except in front of the recording operators' positions A, the troughs D may be arranged with their mouths in substantially the same plane, and they are so shown in Fig. 1. The trough in which the tickets are conveyed from the line operators' positions B to the ticket filing clerk's desk C is shown at E extending before the switchboard positions B and around 75 behind the switchboard and back to the desk C where it terminates in a chute G. Where the troughs D and E extend in a vertical direction, guards F and F' extend substantially parallel to the mouths of the troughs 80 at a short distance therefrom and prevent the tickets from falling from the troughs. Arranged parallel to the troughs D and E is a track H, the construction of which is 85 hereinafter described. Upon this track run 90 a plurality of carriages J and J', also hereinafter described in detail, which carry ticket propelling means in the form of pivoted fingers K and K', which at all times extend 95 over the mouths of the troughs. Normally 100 the propelling finger stands in the position shown at K', but where the troughs D are arranged in step formation in front of the recording operators' positions A, said finger is inclined to the position shown at K by the 105 co-operative engagement of the cam L with the end of said finger. In front of the recording operators' positions A, the cam L carries a guard M which protects the operators from possible injury to their hands by 110 engagement with the end of the propelling finger. Furthermore, the finger is so supported upon the carriage that it is yielding 115 in the direction opposite to the direction in which the finger travels, thereby allowing 110 the finger to yield if it comes into engagement with the operator's hand or any other obstruction in its path. The carriages J and J' may be driven by any suitable means, such as a traveling member in the form of a 115 belt or rope N, to which said carriages are connected in a manner hereinafter described. The rope N is supported by pulleys, certain of which are hereinafter described in detail, and is driven by a plurality of motors O. Owing to the fact that the switchboards at the line operators' positions B are comparatively tall and must be free from the obstruction that would result if the trough E were located within the operator's reach, it is desirable to provide means for elevating and 120 depositing tickets in said trough E. One of said means P is diagrammatically indicated 125

in Fig. 1, and is hereinafter described in detail in connection with Figs. 12 and 13.

Figs. 2 and 3 show in detail the apparatus at the extreme right of the system shown in Fig. 1. The parts are shown mounted upon a base 1 which may be either a part of or separate from the desk C and the switchboards A. The motor O, which may be of any suitable design, is provided with a pulley 2 upon which the rope N runs. Said rope may be supported at intervals by idler pulleys 3 supported on brackets as shown. The troughs D and E and the track H may be supported upon brackets 4, 5 and 6 of any suitable form secured to the base 1 as shown. The cam L may also be mounted on said brackets 5 and 6 through the medium of sheet metal extension brackets 8 and 9 as shown. The detail construction of the track H is hereinafter described in connection with Fig. 7.

Figs. 4 and 5 show in detail the construction of the apparatus at the point where the two horizontal sections are joined by the vertical section. Each stretch of the driving rope N is shown traveling over and under pulleys 12 which may be of the form shown, mounted preferably on ball bearings on brackets 13 secured to inclined bars 14, suitably attached at their lower ends to the base 1 and at their upper ends to a supporting frame 16 which may be suspended from the ceiling of the room by the rods 17. Suitable brackets 19, 20, 21 and 22 support the troughs D and E and the two stretches of track H. The guards F and F', which extend parallel to the mouths of the troughs D and E and prevent tickets from falling therefrom, are supported on auxiliary brackets 24, 25, 26 and 27 of the form shown, which may be secured to the brackets 19, 20, 21 and 22. The auxiliary bracket 25 also helps to support the cam L with which the end of the propelling finger co-operates as hereinbefore explained.

Figs. 6 and 7 illustrate the relation of the troughs D, the track H and the driving rope N on one of the curves, and show how that rope may be supported and also a particular construction of track which has been found very satisfactory. The troughs D and the track H are shown at this point mounted on brackets 30 and 31, which are joined at their outer ends by the curved frame member 32. This frame member 32 serves as a support for brackets 34, of the form best shown in Fig. 7, which carry idler pulleys 35, 36 of the form and arrangement shown, which co-operate with the rope N so as to hold it in the desired relation to the track H. The utility of this particular means for supporting the rope N on curves will hereinafter appear from the description of the means for attaching the carriage to the rope shown in

detail in Fig. 9. It is obvious, however, 65 that the pulleys 35, 36 are so arranged that it is possible for means connected to the rope N to pass between their faces, and this is the object of their peculiar arrangement.

The detail construction of the track H is 70 best shown in Fig. 7. The center portion 40 is composed of some suitable fibrous material, such as leather, and is supported between plates 41 and 42, the three parts being secured together by any suitable means such 75 as rivets 43. Both edges of the fibrous material 40 extend beyond the edges of the plates 41 and 42, and are thus adapted to be engaged by flanged wheels forming a part of the carriage J hereinafter described 80 in connection with Figs. 8, 9 and 10. A track of this kind is particularly desirable when the invention is embodied in a conveying system for telephone toll tickets, because it assists very greatly in obtaining noiseless 85 operation of the apparatus.

Figs. 8, 9 and 10 show in detail a form of carriage which is suitable for a conveying system of the kind hereinbefore generally described. It will be understood, however, 90 that the construction of this carriage may be modified in many respects without departing from the spirit of the invention as set forth in certain of the appended claims covering the apparatus as a whole. Referring to Figs. 95 8, 9 and 10, the carriage as shown is provided with three flanged wheels 50, 51 and 52 adapted to engage the fibrous material 40 forming part of the track H. The wheel 52 is mounted, preferably on ball bearings, 100 upon the lower end of a main frame member 54. The wheels 50 and 51 are mounted in a manner best shown in Fig. 10 in separate supporting frames rotatably and adjustably secured to the ends of a top bar 105 55 forming part of the main frame 54. The supporting frames for the wheels 50 and 51 comprise brackets 57, to which are bolted lugs 59 carrying a flanged wheel 50 or 51 mounted on ball bearings of any well-known 110 form, as best shown in Fig. 10. At their upper ends, the brackets 57 are rigidly secured to a pin 60, having a flange 61 integral therewith and a nut 62 which serves to clamp the bracket 57 firmly in engagement with the flange 61. The pin 60 passes through and is rotatable in a sleeve 64, the outer surface of which is threaded and engages with a threaded hole in the top bar 55, being secured in any desired position by lock nuts 115 65 and 66, as shown in Fig. 10. The sleeve 64 at its upper end may terminate in an enlarged hollow portion 68 adapted to serve as a receptacle for oil-soaked fibrous material, thereby providing for the lubrication 120 of the pin 60 within the sleeve 64. The enlarged portion 68 of the sleeve 64 is covered by a disk 70, which may have an oil-hole 71

125

therein; and the pin 60 may be held from longitudinal movement within the sleeve 64 by means of a washer 72 engaged by a nut 73 with which a lock-nut 74 coöperates. It 5 will be understood that the construction just described permits the flanged wheels 50 and 51 to rotate around the vertical axes formed by the pins 60, as the curvature of the track may require; and that said wheels may be 10 adjusted vertically so that the space between the top of the flanged wheel 52 and the bottom of the flanged wheels 50 and 51 may bear the proper relation to the distance between the top and bottom surfaces of the 15 fibrous material 40 forming part of the track H. The driving connection between the carriage and the driving rope N is best shown in Figs. 9 and 11. This driving connection comprises two links 75 and 76, a yoke 77 to 20 which one end of each of said links is pivotally secured, a double ended screw 78 adapted to pass through holes in said yoke and to screw into the ends of the belt N, and a slotted tube 80 rotatably mounted in flanges 25 81 and 82 secured to the main frame member 54. One end of the link 75 is pivotally mounted within the slotted tube 80 upon the pin 84 which passes diametrically through tube 80; and one end of the link 76 carries 30 a ball member 85 adapted to slide in the tube 80, this being permitted by the slot which allows the links 75 and 76 to take various positions. The rotation of the slotted tube 80 is limited by a lug 86 which projects from it into a slot 87 in the frame member 54. The driving connection just described readily permits changes in the relative location of the belt N and the track H, without imposing excessive strains upon 35 40 either the belt N, the track H or the carriage J; all of which contributes to the quiet operation of the apparatus. The manner in which the propelling finger K is supported upon the carriage is shown in Fig. 8. The 45 parts coöperating with said finger are supported by a bracket 89 secured to the main frame member 54 by screws or bolts 90. Extending from the bracket 89 are lugs 91 through which passes a pin 92 upon which 50 the finger-supporting lever 93 is pivotally arranged. The finger-supporting lever 93 is biased to the position shown by a coiled spring 94 which surrounds the pin 92, the movement of the lever 93 being limited by 55 the engagement of the projection 95 thereon with the lugs 91. Secured to the lever 93 and projecting substantially at right angles therefrom is a pin 96 upon which the bent plate 97 which supports the finger K is 60 mounted. The plate 97 and the finger K are biased to the position shown in full lines in Fig. 8 by a spring 98 which surrounds the pin 96, the movement of said finger being limited by the engagement of the plate 97

with the projection 99 extending from the lever 93. When supported in the manner just described, the finger K is normally held in a line substantially vertical to the plane passing through the wheels 50, 51 and 52 of the carriage. When, however, the finger 70 K engages the cam L, as hereinbefore described, said finger is movable in a vertical plane to the position indicated in dash lines at 100; and if said finger meets any obstruction in the course of its travel along the 75 mouths of the troughs, it will yield to such a position as that indicated in dash lines at 101, thereby preventing damage to the apparatus and allowing the carriage to continue on its way in spite of the obstruction. 80

Figs. 12 and 13 show in detail the means P for elevating and depositing tickets in the trough E, hereinbefore referred to in describing the general arrangement of apparatus illustrated in Fig. 1. Referring to 85 these Figs. 12 and 13, the chute D² is shown projecting downward from one end of one of the troughs D. The front wall of this chute may be slotted, as shown at 105, in order to permit ready clearing of the chute should a 90 ticket become stuck therein; and the bottom end of the chute may be provided with spring clips 106, of the form shown, in order to hold the tickets as they drop and permit their removal in a convenient manner. The 95 trough E, into which tickets are to be deposited, is shown in cross-section in Fig. 13, and in elevation in Fig. 12. The chute D² is supported in brackets 107, 108, which also serve to support certain parts of the 100 ticket elevating and depositing mechanism. This mechanism comprises an arm 110, which may be made in the form of a light metal frame as shown secured to a shaft 111 pivotally mounted in the bracket 108. 105 The shaft 111 carries a gear 112 which meshes with a gear 113 keyed to a shaft 114 also rotatably mounted in the bracket 108. The shaft 114 has secured thereto a pinion 115 which meshes with a rack 116 which is 110 carried by a rod 117, and has a slight longitudinal movement thereon, between collars 118 and 119 secured to said rod 117. At its lower end, rod 117 carries a rack 121 which meshes with a pinion 122 secured to a 115 shaft 123 rotatably mounted in the bracket 107. Secured to the shaft 123 are handles 124, by means of which said shaft may be rotated. At its upper end, the rod 117 is secured to a latch pivoted in a bracket 125, 120 which may be secured to the bottom of the troughs D and E. Said latch serves as a locking means for retaining the pivoted arm 110 in its elevated position, and for this purpose comprises a pivoted body member 125 126 and an inclined toe 127 movably attached to the member 126 through the medium of the leaf spring 128 and adapted

to be engaged by a pin 129 forming part of the arm 110. Behind the toe 127 may be located a resilient stop 130 of rubber or other suitable material with which the pin 128 may engage, and between which and the toe 127 said pin may be locked. The end of the arm 110 carries an article retaining device which may be in the form of a holder 132 attached to the end of said arm, and spring clips 133 secured in the holder 132 as shown. In Figs. 12 and 13, mounted adjacent the trough E in brackets 135, 136 is a chute 137, which coöperates with the ticket retaining device on the end 15 of the arm 110 to release a ticket therefrom and to direct it into the trough E. Located near the outer end of the frame 110 is a pin 141 which coöperates with clips 142 mounted upon the bracket 107, and serves 20 to prevent rebounding of the arm 110 when it is moved to its lower position.

The manner in which the elevating and depositing device shown in Figs. 12 and 13 operates will now be described: In Figs. 12 and 13 the device is shown in full lines in the position in which it is ready to receive a ticket and elevate it; and in Fig. 13 is shown in dash lines in its elevated position after the ticket has been released and deposited. The operator places a ticket between the outer portion of the holder 132 and the spring clips 133, and then moves one of the handles 124 downward. This movement of the handle 124 rotates the shaft 35 123 and the gear 122 which by its coöperation with the rack 121 moves the rod 117 downward. The collar 118 on the rod 117 engages the top end of the rack 116 which in its downward movement causes the rotation 40 of the pinion 115, shaft 114, gear 113, gear 112, and the shaft 111 carrying the arm 110. The lower end of the arm 110 carrying the ticket is thus swung outwardly and upwardly. The downward movement of the rod 117 moves the latch into the position 45 shown in dash lines in Fig. 13; and when the pin 129 engages the toe 127 of the latch the latter yields slightly, owing to the flexibility of the spring by which it is supported and allows the pin to slip into the notch formed between the rear end of said toe and the resilient stop 130. When the pivoted arm 110 reaches the position shown 50 in dash lines in Fig. 13, the spring clips 133 engage the outer wall of the chute 137 and are forced to the position shown in dash lines, thereby releasing the ticket, which drops into the chute 137 and thence into the trough E. The arm 110 may be 55 turned to its original position by raising one of the handles 124. Owing to the lost motion connection between the rod 117 and the rack 116, hereinbefore described, the initial upward movement of the rod 117, 60

caused by the elevation of one of the handles 65 124, will lift the latch, thereby releasing the pin 129 in the arm 110, before the rotation of the shaft 111 is caused by the upward movement of the rack 116 and the consequent rotation of the pinion 115, shaft 70 114, gear 113 and gear 112. Of course, as soon as the spring clips 133 ceases to engage the front wall of the chute 137, they resume the position shown in full lines at the bottom of Fig. 13; and when the arm 75 110 reaches its normal position are ready to receive another ticket. To assist in an understanding of the apparatus shown in Figs. 12 and 13, tickets 140 are shown in dotted lines in the chute D², in the trough 80 E, in the holder 132, and in the spring clips 106.

What is claimed is:

1. In a conveying apparatus, a plurality of troughs arranged adjacent and parallel 85 to one another with their mouths arranged in step formation, and propelling means arranged to move along the mouths of said troughs and to engage articles projecting therefrom.

2. In a conveying apparatus, a plurality of troughs arranged adjacent and parallel to one another with their mouths at some points in the same plane and at other points arranged in step formation, and propelling 95 means arranged to move along the mouths of said troughs and to engage articles projecting therefrom.

3. In a conveying apparatus, a plurality of troughs arranged adjacent and parallel to 100 one another with their mouths at some points in the same plane and at other points arranged in step formation, a track arranged parallel to said troughs, a carriage adapted to run on said track, means for driving said 105 carriage, a resilient propelling finger pivotally supported for movement in two planes perpendicular to each other on said carriage and extending across the mouths of said troughs, and means coöperating with said finger for maintaining the latter adjacent 110 the mouths of said troughs.

4. In a conveying apparatus, a curved track, a traveling member, pulleys arranged 115 to support said traveling member substantially parallel to and outside the curve of said track, a carriage adapted to run on said track, and a universally flexible link connection between said carriage and said traveling member, said pulleys being arranged to engage said traveling member so that said link connection can pass between faces of said pulleys.

5. In a conveying apparatus, a plurality 125 of troughs arranged adjacent and parallel to one another, a guard extending parallel the mouths of said troughs, a resilient propelling finger arranged to move along the

mouths of said troughs between said mouths and the guard and to engage articles projecting from said troughs.

6. In a conveying apparatus, a track, a traveling member, a carriage adapted to run on said track, and a driving connection between said traveling member and said carriage comprising two links one of which is pivotally connected at its ends to said car-

riage and traveling member and the other of 10 which is pivoted at one end to said traveling member and at the other end is pivotally and slidably connected with said carriage.

In witness whereof I hereunto subscribe my name this 28th day of December, A. D. 15 1916.

GEORGE F. ATWOOD.
